UNITED STATES PATENT OFFICE.

JOHN D. RYAN AND PAUL LAUE, OF EAST SAGINAW, MICHIGAN.

SAW-TAB.

SPECIFICATION forming part of Letters Patent No. 288,867, dated November 20, 1883.

Application filed May 21, 1883. (Model.)

To all whom it may concern:

Be it known that we, JOHN D. RYAN and PAUL LAUE, of East Saginaw, in the county of Saginaw and State of Michigan, have invented 5 a new and Improved Saw-Tab, of which the following is a full, clear, and exact description.

Our invention relates to the tabs that are applied to gang and other saws for connection 10 of the buckles used in stretching the saws, and which are always riveted to the saw-plates at an expense of time and labor.

The invention consists in a two-part tab, one portion having lugs or feathers that pass 15 through slots or openings in the saw-plate, as hereinafter described and claimed.

Reference is to be had to the accompanying drawings, forming part of this specification, in which similar letters of reference indicate 20 corresponding parts in all the figures.

Figure 1 is a face view of a portion of a saw with our improved tab. Fig. 2 is a cross-section on line x - x of Fig. 1. Fig. 3 shows the end of the saw-plate with the tab removed. 25 Fig. 4 shows the two portions of the tab separated. Fig. 5 is an end view of the same.

A is the saw-plate, and B B' the two plates forming the tab. One plate, B, as shown, is formed with lugs or feathers a , preferably 30 three in number, that pass through slots or openings b in saw-plate A. The outer faces of lugs a are wider than the slots b , and the edges of the lugs and their plate B are undercut or recessed, so that their edges lap over 35 the edges of the slot, and thereby assist in holding the plate B, and also give a hold for the straining-buckle. The other tab-plate, B', is placed against the opposite face of the saw-plate, and, a screw or rivet, c , being put 40 through the tab, is held securely without any

possibility of its shifting or being torn away by the strain. The plate B' is preferably recessed, as shown, to fit the lugs a , so as to strengthen the parts.

This tab can be readily applied without the 45 labor of applying three or more rivets, as usually required, and when in place the strain is not upon rivets, but upon the lugs, which have ample strength. It can also be removed easily without injury, while the riveted tabs are 50 frequently broken by removal; and our tab being practically indestructible by ordinary use, the frequent expense of new tabs is saved. Thus, in the respects of utility, durability, and economy, our improved tab is greatly superior.

Having thus described our invention, we claim as new and desire to secure by Letters Patent—

1. A saw-tab consisting of two plates, one 60 of which is provided with lugs for entering apertures of a saw, and between which plates the saw is to be secured, substantially as shown and described.

2. The combination, with a saw having apertures b , of the plate B, provided with the lugs a , and the plate B', the said plates being placed on opposite sides of the saw and secured together by a screw, substantially as herein shown and described.

3. The combination, with a saw having apertures b , of the plate B, provided with the lugs a , having undercut edges, the plate B', and the screw c , substantially as herein shown and described.

JOHN D. RYAN.
PAUL LAUE.
